(57) **CLAIM**

The ornamental design for a soap dispenser spout as shown and described.

DESCRIPTION

FIG. 1 is a perspective view of a soap dispenser spout of the new design;

FIG. 2 is a front elevational view of the soap dispenser spout of FIG. 1;

FIG. 3 is a left side elevational view of the soap dispenser spout of FIG. 1;

FIG. 4 is a right side elevational view of the soap dispenser spout of FIG. 1;

FIG. 5 is a rear elevational view of the soap dispenser spout of FIG. 1;

FIG. 6 a top plan view of the soap dispenser spout of FIG. 1; and,

FIG. 7 is a bottom view of the soap dispenser spout of FIG. 1.

The broken lines shown in the figures represent portions of the soap dispenser spout that form no part of the claimed design.

1 Claim, 6 Drawing Sheets(56)
